Application December 18, 1933, Serial No. 702,960

12 Claims.

This invention relates to safeguarding repositories, especially against unauthorized tampering therewith. In one embodiment of the invention, there is provided a safety device for locking and unlocking cooperating mechanisms, more particularly as to cash drawers.

Referring to the drawings:

Fig. 1 is a front elevation, parts being broken away, of a cabinet having features of this invention incorporated therewith;

Fig. 2 is a plan view on the line II—II, Fig. 1;

Fig. 3 is a view on the line III—III, Fig. 2, parts being broken away;

Fig. 4 is a section on the line IV—IV, Fig. 2;

Fig. 5 is a section on the line V—V, Fig. 2;

Fig. 6 is a section on the line VI—VI, Fig. 2; and

Fig. 7 is a wiring diagram of the electrical control connections embodied herein.

Cabinet or general housing 1 is shown as having opening 2 therein. From this opening 2 there extend anti-friction ways comprising lower rollers 3 and upper rollers 4 effective to engage therebetween track 5 from the side 6 of repository or drawer. This drawer or receptacle may have compartments 7, 8, with front 9 as a closure for the opening 2 of the cabinet 1. The drawer has rear portion 10 carrying brackets 11 mounting compression springs 12 directed into concave sockets 13 mounted by brackets 14. These springs 12 normally in compressed position when the drawer front 9 is in closed position at the opening 2 thus tend normally to shift the drawer toward opening position.

This drawer has bottom 15 from which extends bar 16 (Fig. 4) with upstanding offset 17 adapted to be engaged by catch 18, normally thrown downward into such engagement position by compression helical spring 19. This spring 19 abuts washer 20 at pin 21 and bracket 22 opposing this pin 21. The spring 19 has extending therethrough this catch 18 and upward from the bracket 22 has pivot pin 23 to provide connection with the lever 24 having fixed fulcrum 25 at housing 26. This lever 24 extends past the fulcrum 25 to pivot connection 27 with core 28 of coil or solenoid 29 in bracket 29 carried by the housing 26.

The cabinet 1, at a convenient location adjacent the drawer front 9 has push bottom switch 30 (Figs. 1, 7). There may be a source of electric current supply, say as normal power line of 110 volt, 60 cycle, supplied by lines 31 past fuses 32 to transformer 33. From this transformer 33, line 34 extends to the switch 30. Upon closing

(CL. 70—50)

this switch 30, line 35 therefrom extends as a circuit through the coil 29 past switch 36, and by line 37 completing the circuit to the transformer 33. It is thus seen that upon closing the switch 30, the energizing of the solenoid 29 causes the core 28 to descend therewith, thus lifting the latch 18, so that the springs 11 are at once effective in thrusting the drawer to open position clear of this latch 18. The operator may then draw the drawer out to the fully open position. It is thus seen it is only necessary to close the switch momentarily for the drawer to be snapped open. Upon release of the switch 30, the operator may close the drawer against the action of the springs 12 and the offset 17 rides under the beveled portion of the latch 18 and the spring 19 re-sets this latch.

This housing 26 is in compartment 38 (Fig. 2) in the rear of the drawer. Additionally, there is a compartment 39 isolated from this compartment 38 by door 40 having hinge 41 and latch 42. The compartment 39 is closed against ready access by door 43 mounted on hinges 44 and held in closure position by lock 45 at the rear of the cabinet 1.

While the push button switch 30 may be in a special or concealed location against unauthorized access to this cash drawer, there may be herein emergency provision by additional push button switch or switches 46 at scattered or remote locations. Upon closing a switch 46, circuit may be established from the line 37 by line 47 to line 48, having therein solenoid coil 49 and from thence by line 50 to the line 34. There is completed a second circuit from the transformer 33. Energizing this coil 49 acts on core 51 to open the switch 36. It is thus seen that any switch 46 which has been closed, renders ineffective any closing of the switch 30 to release the catch for opening the cash drawer. Furthermore, if there be no circuit at switch 30, the drawer is likewise locked, for neither the switch 30 nor the switch 46 may be effective. Electric current is required to release the drawer for opening, and electric current may interpose to render such release ineffective.

The solenoid coil 49 is mounted in bracket 52, located in the chamber 38. The solenoid core 51 has extension pin 53 embraced by compression helical spring 54 normally acting against disk 55, yieldably to position the cross terminal switch 36. This spring 54 is above enlargement 56 on this solenoid core 51. This enlargement 56 provides shoulder 57. Against this enlargement 56, plunger 58 is normally urged by compression

spring 59, acting between bracket 60 (Fig. 2) and pin 61.

Accordingly, as this solenoid 49 is energized, the core 51 is lifted, opening the switch 36, thereby allowing the spring 60 to thrust the plunger 58 under the enlargement 56 to engage the shoulder 57. The switch 36 is thus locked in open position and may not be re-set for effective operation of the release mechanism of the cash drawer until re-setting has occurred. This re-setting may be effected by unlocking the lock 45, opening the door 43, grasping enlargement 62 on the stem 58, pulling such into the compartment 39, thus to allow a weight 68 to be effective in lowering the core 51, and thus closing the switch 36. This enlargement or head 62 may then be released and the plunger 58 rest against the enlargement 56 above the shoulder 57.

20 Fixed with this core 51 is switch 63, which, upon opening of the switch 36, may be closed, thus completing electric current in a third circuit from the line 37 by line 64 to line 65, to alarm as a bell 66, then by line 67 to the line 34. 25 This alarm may be visible or audible or both, and be an additional safety or safeguard for the cash drawer installation, which at the cabinet 1, may be in association with merchandise display, cash register, or desired mechanism relevant to the business of the installation.

30 Outward shifting of the drawer is limited by projection 69, at the rear portion 10 of the drawer, abutting stop 70 fixed with the case or cabinet 1.

35 It is to be understood that the operation of the solenoids or coils 29, 49, is not to be sluggish, and accordingly the winding or voltage is adapted thereto and may be, in instances, for taking line current instead of through a transformer.

40 What is claimed and it is desired to secure by Letters Patent is:

1. A receptacle, a way therefor, a housing for the receptacle and way, said housing having an opening for travel of the receptacle from the housing in its movement along the way into opening position, means normally acting to thrust the receptacle into opening position, a catch for retaining the receptacle in closed position against the action of said means, an electric control circuit in the housing for the catch, a manually operable switch accessible adjacent the housing for rendering the control circuit effective to release the catch and thereby free the means for thrusting the receptacle into open position as to the housing, an additional electric switch remote from the housing, and a circuit between the housing and the additional electric switch, said additional electric switch being operable for rendering the control circuit ineffective in release of the receptacle.

2. A receptacle, a way therefor, a housing for the receptacle and way, said housing having an opening for travel of the receptacle from the housing in its movement along the way into opening position, means normally acting to thrust the receptacle into opening position, a catch for retaining the receptacle in closed position against the action of said means, a primary control including an electric circuit for releasing the catch, and a secondary control including an additional electric circuit for rendering the primary control ineffective.

3. A receptacle, a way therefor, a housing for the receptacle and way, said housing having an opening for travel of the receptacle from the

housing in its movement along the way into opening position, means normally acting to thrust the receptacle into opening position, a catch for retaining the receptacle in closed position against the action of said means, a primary control for releasing the catch, a secondary one way control rendering the primary control ineffective, and re-set means for re-positioning the secondary control for a succeeding one way operation.

4. A cash drawer, a catch for holding the drawer against opening, a solenoid operator for the catch, a circuit for the solenoid, a first switch for closing said circuit to energize the solenoid in effecting release of the catch, a second switch in said circuit, a second circuit effective to open said second switch, and a catch for holding said second switch open.

5. A cash drawer, a catch for holding the drawer against opening, a solenoid operator for the catch, a circuit for the solenoid, a first switch for closing said circuit to energize the solenoid in effecting release of the catch, a second switch in said circuit, a second circuit effective to open said second switch, a catch for holding said second switch open, and release means for the catch to effect re-setting of the second switch.

6. A cash drawer, a catch for holding the drawer against opening, a solenoid operator for the catch, a circuit for the solenoid, a first switch for closing said circuit to energize the solenoid in effecting release of the catch, a second switch in said circuit, a solenoid for the second switch, a second circuit for energizing the second switch solenoid to open said second switch, a plunger, and a switch effective to shift the plunger to hold the second switch open.

7. A cash drawer, a catch for holding the drawer against opening, a solenoid operator for the catch, a circuit for the solenoid, a first switch for closing said circuit to energize the solenoid in effecting release of the catch, a second switch in said circuit, a solenoid for the second switch, a second circuit for energizing the second switch solenoid to open said second switch, a plunger, a switch effective to shift the plunger to hold the second switch open, and unauthorized-access-precluding means to hinder withdrawal of the plunger for re-setting the second switch.

8. A cash drawer, a cabinet therefor having exterior of the drawer a compartment, control mechanism in the compartment including catch and release mechanism for the drawer, a re-set, and unauthorized-access-precluding means for restricting the re-set to authorized operation.

9. A drawer, side rails therefor, a housing for the drawer, rolls mounted by the housing to embrace the rails in sustaining the drawer in the housing, a spring normally shifting the drawer from the housing, a catch in the housing for retaining the drawer against shifting by the spring, a solenoid for withdrawing the catch, a first circuit for the solenoid including a normally manually operable switch, an additional electrically operable switch for said circuit, and a second circuit for operating the additional switch.

10. A drawer, side rails therefor, a housing for the drawer, rolls mounted by the housing to embrace the rails in sustaining the drawer in the housing, a spring normally shifting the drawer from the housing, a catch in the housing for retaining the drawer against shifting by the spring, a solenoid for withdrawing the catch, a first circuit for the solenoid including a normally manually-operable switch in the housing, an ad-

ditional electrically-operable switch for said first circuit, cut-out means and a second circuit between the housing and the cut-out means normally leaving said additional switch to be effective through the first circuit to control the catch, said cut-out means being operable, for rendering the additional switch ineffective for re-operation.

11. A drawer, side rails therefor, a housing for the drawer, rails mounted by the housing to embrace the rails in sustaining the drawer in the housing, a spring normally shifting the drawer from the housing, a catch in the housing for retaining the drawer against shifting by the spring, a solenoid for withdrawing the catch, a first circuit for the solenoid including a normally manually-operable switch, an additional electrically-operable switch for said circuit, cut-out means, a second circuit between the housing and the cut-out means normally leaving said additional switch to be effective through the first circuit to control the catch, said cut-out means being operable for rendering the additional

switch ineffective for re-operation, and unauthorized access-hindering means for the cut-out.

12. A drawer, side rails therefor, a housing for the drawer, rails mounted by the housing to embrace the rails in sustaining the drawer in the housing, a spring normally shifting the drawer from the housing, a catch in the housing for retaining the drawer against shifting by the spring, a solenoid for withdrawing the catch, a first circuit for the solenoid including a normally manually-operable switch, an additional electrically-operable switch for said circuit, cut-out means, a second circuit between the housing and the cut-out means normally leaving said additional switch to be effective through the first circuit to control the catch, said cut-out means being operable for rendering the additional switch ineffective for re-operation, unauthorized access-hindering means for the cut-out, and authorized entrance mechanism to said additional switch.

CHARLES F. MEILINK.
